(57) **CLAIM**

The ornamental design for a cat wand, as shown and described.

DESCRIPTION

FIG. 1 is a top, front, right side perspective view of a cat wand, showing my new design;

FIG. 2 is a front view thereof;

FIG. 3 is a back view thereof;

FIG. 4 is a left side view thereof;

FIG. 5 is a right side view thereof;

FIG. 6 is an enlarged top view thereof;

FIG. 7 is an enlarged view of the portion labeled "7" framed in FIG. 1;

FIG. 8 is an alternative perspective view of the cat wand in extended state; and,

FIG. 9 is an alternative perspective view of the cat wand with its wand and handle shown separately.

The broken lines in the drawings depict environmental subject matter only and form no part of the claimed design. In FIG. 1 and FIG. 7, a broken line rectangular frame defines the boundary of an enlarged view and forms no part of the claimed design.
